UNITED STATES PATENT OFFICE.

ORVILLE D. CARLISLE, OF BUCHANAN, MICHIGAN.

IMPROVEMENT IN CARPET-STRETCHERS.

Specification forming part of Letters Patent No. 172,087, dated January 11, 1876; application filed November 9, 1875.

To all whom it may concern:

Be it known that I, ORVILLE D. CARLISLE, of Buchanan, in the county of Berrien and State of Michigan, have invented certain new and useful Improvements on Carpet-Stretchers, of which the following is a specification:

The nature of my invention relates to the construction of a device by which a carpet can be smoothly stretched on the floor of the apartment to which it is to be tacked; and it consists in a bar, which is to be temporarily attached to the floor, on which is supported a roller, which is actuated by a lever and gear, to roll up two straps attached to a spiked bar which engages with the carpet. There is also provided means whereby the device carrying the roller may be rotated so as to bring the said roller and spiked bar parallel to the main bar, so that the device may be readily packed for transportation.

Figure 1 is a perspective view of my invention. Fig. 2 is a section on the line $x-x$, and Fig. 3 is a section on the line $y-y$.

In the drawing, A represents the main bar, to one end of which is secured the spike B, which is provided with a head, b, and the projection b' , to prevent its too close contact with the base-board. On the bar A is secured a journal-box, C, in which rotates the roller D, which is secured in the journal by the collar d, on one side, and on the other side by the face-gear E, rigidly attached to the roller. The face-gear engages with a spur-gear, F, which is attached to the journal-box C by the pivot f, the spur-gear having secured to its upper face a lever, G, by which it is rotated. On the bottom of the journal-box are two projections, $c c'$, the former of which is provided with a stud, e, to which is pivoted a dog, h, which engages with teeth or ratchet of the face-gear, and prevents the roller from unwinding the straps. The projection c is also provided with a bolt, i, which passes through the bar A, and secures the journal-box to said bar, and permits the journal-box to rotate un-

til the roller D is brought parallel to the bar A. To the bar A is attached a button, k, which engages with the projection c' , and keeps the journal and gears in place when in use, while the lug c^2 prevents the journal-box from turning past the bar A. To each end of the roller D are secured straps H, the other ends of which are attached to the bar I, which has driven diagonally through it the spikes m, which engage with the carpet. On the upper side of the bar I is pivoted a button, n, which engages with bar A, and holds bar I in place. The carpet being tacked down on one side of the room, the spike B is driven into the floor near the other edge of the carpet, the bar A extending toward the carpet. The spike-bar I is attached to the carpet by means of the spikes m' . By rotating the spur-gear F by means of the lever the roller D is caused to revolve and wind up the straps H, which necessarily draw forward the spike-bar I, and stretch the carpet, which can then be tacked in place. The dog h, engaging with the teeth of the face-gear, prevents the roller from yielding to the strain of the carpet.

What I claim as my invention is—

1. In a carpet-stretcher, the combination of the bar A, the pivot f, the journal-box C, and roller D, substantially as set forth.
2. In a carpet-stretcher, the combination of the bar A, journal-box C, roller D, face-gear E, spur-gear F, and lever G, substantially as described.
3. The combination of the journal-box C, roller D, face-gear E, spur-gear F, lever G, straps H, and spike-bar I, substantially as described.
4. The combination of the bar A, journal-box C, roller D, face-gear E, spur-gear F, lever G, straps H, and button k, substantially as and for the purposes set forth.

ORVILLE D. CARLISLE.
